W. E. GUNNERSON

ADAPTER

Filed March 30, 1923

Inventor:
Walter Ernest Gunnison.

Br Foré Bain & Hinkle - 1115

Patented Oct. 27, 1925.

UNITED STATES PATENT OFFICE.

WALTER ERNEST GUNNERSON, OF MILTON, WISCONSIN, ASSIGNOR TO BURDICK CABINET COMPANY, OF MILTON, WISCONSIN, A CORPORATION OF WISCONSIN.

ADAPTER.

Application filed March 30, 1923. Serial No. 628,726.

To all whom it may concern:

Be it known that I, WALTER ERNEST GUNNERSON, a citizen of the United States, residing at Milton, in the county of Rock and State of Wisconsin, have invented certain new and useful Improvements in Adapters, of which the following is a specification.

This invention relates to adapters.

It will be explained as applied to an adapter for use with therapeutic lamps.

Some of the appliances or applicators used with therapeutic lamps in the treatment of disease are in the form of rods of quartz and other suitable materials. Such rod like applicators are primarily used to direct and apply the lamp's rays to body cavities. The adapter hereinafter set forth is particularly adapted to attach such applicators to therapeutic lamps.

An example of a therapeutic lamp with which the herein-described adapter may be used is disclosed in United States Patent No. 1,435,193; granted November 14, 1922.

One of the objects of this invention is to provide an improved adapter.

Another object is to provide an adapter which will readily accommodate a variety of shapes and sizes of applicators.

Another object is to provide an adapter particularly adapted to receive and hold rod shaped applicators.

Another object is to provide an adapter which is simple, reliable, inexpensive and readily manipulated.

Other objects and advantages will herein-after appear.

An embodiment of the invention is illustrated in the accompanying drawing, wherein—

Fig. 1 is an outline perspective of a typical therapeutic lamp with an adapter for application thereto.

Fig. 2 is an enlarged separated perspective of the adapter, and

Fig. 3 is a longitudinal section thereof.

Adapter 1 is adapted for attachment to a therapeutic lamp 2 and to hold an applicator 3. Both the lamp and the applicators may take various forms. Ordinarily the

lamp comprises a suitable casing or housing, a ray generator, such as a mercury vapor tube, within the casing and the necessary electrical connections and terminals. Often the casing is double walled to permit

circulation of a cooling fluid, and then water

or other fluid connections are provided. The applicators often take the form of rods or stems of various lengths, sizes and shapes. Such applicators are ordinarily employed to direct or conduct the rays from the lamp into cavities of the body. It is highly desirable that a variety of different applicators may be readily applied to and removed from a single lamp.

The applicator has an attaching plate 5 which may be of substantially flat and circular shape. Plate 5 has a rearwardly projecting annular flange 6 which may be knurled to provide a surface which may be readily grasped to apply and remove the same from a lamp. Flange 6 may have rearwardly projecting locking lugs 7. These lugs may fit into corresponding slots in the lamp casing or they may be adapted to fit into slots of a lamp attaching unit or section such as set forth in Fritz A. Anderson application Serial No. 514,217; filed November 10, 1921.

Plate 5 has a forwardly projecting tubular hub 8 whose bore, when the plate is in position, aligns with the ray projecting opening 9 of the lamp casing. The rear portion 10 of hub 7 is enlarged and exteriorly threaded. The forward reduced portion of hub 7 is divided or bifurcated into two similar segments 11 by longitudinal slots 12. Segments 11 are beveled or sloped toward their outer or forward ends, and, throughout the bevel, slots 12 are enlarged to form jaw recesses 13. An annular shoulder 14 marks the junction of the reduced and enlarged portions of hub 8.

The bore through hub 8 is reduced in diameter near its rear end to provide a shoulder 15.

A pair of similar jaws 16 are interconnected by a small U shaped biasing and supporting spring 17. The ends of the legs of spring 17 are secured in holes in the base surfaces of jaws 16. The yoke 18 of spring 17 is bent at substantially a right angle to the plane of the legs of the spring so as to form a foot, adapted to rest upon shoulders 15. The yoke is curved so as to remain clear or outside of the reduced bore of the hub and not obstruct the passage of the rays. One of the jaws 16 slidably lies in each jaw recess 13 and is supported by spring 17 with its inner end slightly above the back of the recess so as to give sufficient

clearance for the movement of the jaws. Jaws 16 are tapered or flared from front to back so that they may be forced together as will be hereinafter described.

- 5 5 An internally threaded tubular cap 20 is adapted to screw upon the threaded rear portion 10 of hub 8. The forward end of the bore of cap 20 is frusto-conical shaped, approximately to correspond to the taper or 10 slope of jaws 16.

The tendency of spring 17 is to separate jaws 16 but, when cap 20 is screwed upon hub 8, the interaction of the sloping or tapered surfaces of the jaws and the bore of 15 the cap provides a wedging action which forces the jaws together against the bias of spring 17. The jaws are caused to approach as the cap is turned back so that the clamping action of the jaws upon an applicator lying therebetween may be varied as 20 desired. When cap 20 is screwed outwardly the wedging action decreases and the bias of spring 17 separates the jaws.

Applicators may be readily applied to the 25 lamp by inserting them between the jaws of the adapter, where they are in the path of the rays, and then turning the cap to cause the jaws to clamp. An applicator is readily released by turning the cap of the 30 adapter in the reverse direction. The clamping faces of the jaws may be formed to meet any special and peculiar condition as to shape of applicator. If necessary, each adapter may have several sets of jaws 35 and springs assembled into units which may be interchangeably applied by merely removing the cap.

Having described my invention what I 40 claim as new and desire to secure by Letters Patent, is:—

1. An adapter for attaching applicators to a therapeutic lamp and comprising, a hollow hub for attachment to the lamp and through which the light may pass, applicator clamping jaws adapted to be moved toward and from each other to clamp and release an applicator therebetween, resilient means for supporting the jaws on the hub and affording an unobstructed light passage to an applicator held by the jaws and acting to bias the jaws apart, and a cap co-

operating with the hub and jaws to hold the same together and so that movement of the cap in one direction causes the jaws to approach each other and movement in the 55 other direction permits the jaws to separate.

2. An adapter for attaching applicators to a therapeutic lamp and comprising, a hollow threaded hub, a pair of relatively movable clamping jaws, a spring for holding and biasing the jaws apart, said spring being formed so as not to obstruct the passage of light through the bore of the hub, and a hollow cap adapted to be threaded upon the hub and acting upon the jaws to 60 force the same together against the tension of the spring.

3. An adapter for attaching applicators to a therapeutic lamp and comprising, a plate for attachment to a lamp and having an opening therethrough; a tubular exteriorly threaded hub on the plate, the bore of the hub aligning with the opening in the plate and having a shoulder therein; a spring resting on the shoulder in the bore 75 of the hub; a pair of jaws supported and biased apart by the spring; and a cap threading upon the hub and acting upon the jaws to force the same together against the bias of the spring.

4. An adapter for attaching applicators to a therapeutic lamp and comprising, a plate for attachment to a lamp and having an opening therein for the passage of light; a slotted tubular exteriorly threaded hub 85 projecting from the plate, the bore of the hub aligning with the opening in the plate and having a shoulder therein; a substantially U shaped spring whose legs lie parallel to the bore of the hub and whose base is curved so as not to obstruct the passage 90 of light and formed at an angle to the legs to provide a foot for resting on the shoulder about the bore of the hub; a pair of cooperating jaws, one carried by each leg of 95 the spring and lying in one of the slots of the hub; and a threaded cap for application to the hub and cooperating with the jaws to move the same.

In testimony whereof I hereunto subscribe my name.

WALTER ERNEST GUNNERSON.
